CLOSURE DEVICE WITH SEPARABLE FASTENERS FOR CLOTHS AND THE LIKE

Apollon Tchekhovitch, Paris, France

Application February 23, 1933, Serial No. 658,181
In Belgium November 30, 1932

8 Claims. (Cl. 24—207)

The invention relates to a closure device, particularly applicable to cloths, under cloths and all other articles made of flexible materials and comprising members fixed in spaced relation or at 5 intervals on a band and adapted to slide on flanges provided on the edges to be united.

One object of the invention is to avoid the crumpling or frowning as well as the wear of the fabric and to insure straight sliding movement 10 of the fastening members without rubbing and jamming.

Another object of the invention is to enable the closure to be easily locked and unlocked in any desired position.

According to the invention, the fastening members are fixed in spaced relation to the band, which band may be also formed as a chord like member and said fastening members are provided with notches formed in the side faces of said members 15 adapted to accommodate the folds formed on the band between the members when said members are moved towards and in contact with each other.

The fastening members are provided with side openings accommodating the flanged edges to be 20 united and either the band surrounds the lower parts of the fastening members to be fixed thereto substantially in the central plane passing through the side openings, or the fastening members are provided with a flat base applied against the band 25 the latter thus retaining the members in a straight position when a pull is exerted thereon to operate the closure.

According to another feature of the invention the closure device is provided with locking means 30 comprising strings or cords one of the ends of which is of larger diameter than the other and passing through holes provided in the leading member, said strings or cords being provided with knots, pearls or the like and the arrangement being such that when a pull is exerted on the thin 35 ends of the strings or cords the flange or flanges is or are jammed in the hole or holes of the fastening member while when a pull is exerted on the thick end of the strings or cords the jamming action is removed.

According to another feature of the invention the ends of the flanges are provided with plate-like 40 members having sliders mounted thereon, said sliders forming stops for the fastening members or enabling the latter to be removed from the edges to be united, according to whether said sliders are placed adjacent said edges or moved away therefrom.

Other features and advantages of the invention 45 will become apparent from the following descrip-

tion in reference to the annexed drawing in which:

Fig. 1 is a front view of a closure in accordance with the invention, illustrated in closed position;

Fig. 2 illustrates said closure in the open position;

Fig. 3 shows diagrammatically a part longitudinal section along line III—III of Fig. 1, showing a closure device the fastening members of which are fixed in accordance with the invention; in this 10 view each fastening is illustrated in section obtained substantially along line 3—3 Fig. 4.

Fig. 4 is a sectional view through a fastening member, the section being taken along the line 15 IV—IV of Fig. 1;

Fig. 5 is a sectional view through a leading member, the section being taken along the line V—V of Fig. 1;

Fig. 6 is an end view of a pair of stop plates according to the invention;

Figs. 7 and 8 are elevational views of two forms of a leading member according to the invention;

Fig. 9 illustrates in sectional elevation another form of leading member;

Fig. 10 shows the fastening member of Fig. 9 20 inserted in the closure device;

Fig. 11 illustrates in longitudinal section a series of fastening members provided with notches adapted to accommodate the folds of the band when the closure is in the closed position;

Fig. 12 illustrates said fastening members in the open position of the closure; and,

Fig. 13 is a view similar to Fig. 11 of another form of fastening members.

The closure in accordance with the invention 35 comprises a series of fastening members 1 fixed in spaced relation, as by stitching, on a band 2 and sliding on to the parts 3 to be united. These parts are provided with flanged or corded edges 40 (Figs. 1 and 2).

In prior closures of this type, the fastening members were fixed to the band by that face thereof which is remote from the central plane containing the lateral openings accommodating 45 the edges to be united, with the result that when a pull was exerted on the band the fastening members were reaching an inclined position causing the jamming thereof on the edges of the fabric and soon wearing out the latter, the operation 50 of the closure being moreover difficult. In accordance with the invention, the fastening members are fixed to the band through their middle or central point, that is to say through a point lying approximately in the plane containing the 55

flanges or corded edges on which the fastening members are adapted to slide.

This method of fixing the fastening members is illustrated in Figures 3 and 4, showing that the band 2 has been stitched on the members 1 along its middle or central line, so as to surround the adjacent or lower part of each member and so that the said members are fixed to said band at points lying on the longitudinal, vertical and central axis as shown in Fig. 3 and centrally in each member as shown in Fig. 4.

Such stitching may be performed, for example, by means of threads 5 passing through the central holes 26 of the fastening members.

15 When the leading member 6 is moved from the position shown in Fig. 1 to that illustrated Fig. 2, the fastening members are applied against each other by their middle or central portion with the result that they slide quite freely.

20 Owing to the arrangement illustrated in Figs. 3 and 4 when a pull is exerted on the leading member 6 to move the closure from the position shown in Fig. 2 to that illustrated in Fig. 1, the pull which is applied to the fastening members lies substantially in the plane of the resisting rubbing forces and passes substantially through the central portion of said members, so that they slide as freely as before without any tendency of tilting and jamming.

25 As will be seen in Fig. 4, the slots 7 in which pass the edge parts 3 of the fabric are relatively long and they are further arranged in line with one another in the plane containing the axis of the holes 8 accommodating the flanges 4.

30 Owing to this arrangement the ends of the slots 7 have no tendency to wear out the edge portions of the fabric, while instead of crimping or frowning and of jamming in the holes 8 as with certain known fastening members, said edge portions are flattened between the two faces of the slots 7.

35 The wear is still further reduced by forming the holes 8 as well as the slots 7 of relatively large sizes and making the flanges relatively thick.

40 The axial connection of the fastening members could also be insured by passing or stitching them on a cord instead of stitching them on a band.

45 It will be observed that in the arrangement in accordance with the invention the band 2 does not pass through the slots 7 or the holes 8, so that there will be no contact between said band and the edges to be united and rubbing on said edges as well as crumpling of the band by forming small folds between the surfaces of the holes 8 and the edges to be united are avoided.

50 Fig. 5 illustrates a leading member 6 provided with a locking device in accordance with the invention.

55 Said device comprises two small cords 9 passing through the holes 8 and thickened at one of their ends. Their thin ends are united together and to a pearl 10, while the thick ends are fastened to two pearls 11 (or also united with one another and with a tassel).

60 When a pull is exerted on the pearl 10, the thick ends of the cords are engaged in the holes 8 causing the jamming of the flanges 4 therein. Owing to this arrangement the closure device may be retained in closed position as illustrated in Fig. 1, or in any intermediate position between the open and closed positions.

65 When a pull is exerted on the pearls 11, the thin ends of the cords are engaged in the holes 8 and the jamming action on the flanges 4 is removed, owing to the holes 8 being made large enough to enable the sliding movement of the

flanges even with the thin ends of the cords therein.

Such a position of the cords is illustrated in Fig. 2.

To open the closure device it will be sufficient to exert a pull on the pearls 11 (in downward direction in Fig. 1) and as such pull is exerted in the plane of the edge portions of the fabric and as the thin ends of the cords encircle the center of the leading member, the movement of the 10 fastening members is effected without difficulty.

To close the device it is sufficient to exert a pull (in upward direction in Fig. 2) on the leading member 6 and at or about the end of this movement, to pull in turn the pearl 10 so as to lock the 15 closure in the desired position.

The flanges in accordance with the invention are formed with flattened ends and connected therethrough to end plates 16 (Figs. 1, 2 and 6). Each of these plates is provided with a slider 17 20 mounted thereon by means of an extension 18 passing through a slot 19.

When the sliders are moved to the position illustrated in Figures 2 and 6, the flanges are in line with the plate ends supporting the sliders 25 and the total thickness of these parts is such that they cannot pass through the slots 7 of the fastening members. In this manner these plates and sliders form stops for the fastening members.

When it is desired to remove the fastening 30 members, as for example in order to enable the cloth on which the closure is mounted to be cleaned it is sufficient to move the sliders to the positions illustrated in Fig. 1, as in such a case the plates alone, which can be easily passed 35 through the slots 7, are encountered by the fastening members and the latter are then capable of being removed one at a time when moved on to the plates.

Fig. 7 illustrates a leading member of ogee 40 shape which member is to be held at the top and the bottom thereof to operate the closure.

Fig. 8 represents another form of leading member which is to be held at the sides thereof, such a mode of holding the member being more convenient. The upper part of the member is larger than the lower part thereof, so that the fingers come in contact with the upper part only without a pressure being exerted on the fabric the latter being thus able to slide freely through the slots 50 of the member. Such a fastening member has the shape of a flat bar or broach and terminates harmoniously with the closure.

In Figs. 9 and 10 a leading member is illustrated which is provided with a transverse hole 55 20 accommodating a loop 21 formed of a silk or metal thread and having a tassel 22 mounted thereon. In such a case the closure may be opened and closed by pulling the tassel in one or the other direction as the overhanging is of 60 reduced value.

In the fastening members which are provided with stitching holes to enable them to be stitched on the band in the usual manner, these stitching holes terminate on the faces of the fastening 65 members which are opposite and in contact with one another when the closure is moved in the opened position (Fig. 2).

In the usual mounting of the fastening members the threads passing out from these holes to 70 pass through the band are applied against each other and interposed between the lower parts of the fastening members when the closure is moved in the opened position.

In the arrangement in accordance with Figs. 75

3 and 4, aside from these threads, portions of the band are also extended to the stitching holes.

When the fastening members are moved against each other, to open the closure, the lower parts of the fastening member remain spaced from one another with the thickness of the threads and of the folds of the band, and the chaplet so formed takes a curved form i. e. the shape of a scorpion tail, rendering thus the closing movement very difficult.

To avoid this drawback, and in accordance with the invention, the stitching holes terminate in notches 23 (Figs. 11 and 12) adapted to accommodate exactly the thicknesses of the band folds 28 interposed between the fastening members, so that the latter remain in straight and correct position when moved against each other (Fig. 12).

Instead of the fastening members being stitched by their middle or central part to avoid their twisting or rotating movement, as illustrated in Figs. 3, 4, 5, 11 and 12, said members may be also secured as illustrated in Fig. 13.

In this figure, instead of being formed with a rounded lower face, the fastening members 1 are provided with a flat face 24 firmly secured as by stitching threads 5 on the band 2.

The stitching holes 26 terminate again into notches such as 23 and on either side of the face 24 small notches 25 are formed and adapted to accommodate the folds of the band so that when the fastening members are moved together they will lie flat against each other.

When a pull is exerted on the band (or on the leading member) in order to move the device in the closed position, the band remains straight because it is taut, and the fixing of the fastening members prevent their rotating movement (in anticlockwise direction in Fig. 13), and remain in correct position without jamming on the edges to be united.

It is to be understood that the invention has been described and illustrated by way of example and that modifications may be made therein without departing from the spirit thereof.

I claim:

1. A closure device for cloths and other articles made of flexible materials comprising flanged edges to be united and separated, a flexible band, fastening members provided with side openings accommodating said flanged edges, said fastening members being fixed in spaced relation to said band, and notches in the side faces of said members to accommodate the folds of the band between the members when the latter are adjacent to and in contact with each other.

2. A closure device for cloths and other articles made of flexible materials comprising flanged edges to be united and separated, a flexible band, fastening members fixed in spaced relation to said band, notches in the side faces of said members to accommodate the folds of the band between the members when the latter are moved adjacent to and in contact with each other, side openings in the fastening members accommodating the said flanged edges and the said openings located in one and the same plane and substantially the plane in which the fastening members are fixed to the band.

3. A closure device for cloths and other articles made of flexible materials comprising flanged edges to be united and separated, a flexible band, fastening members fixed in spaced relation to said

band, a leading member on said band, said leading member having a thicker part above the band and notches in the side faces of all the fastening members, adapted to accommodate the folds of the band between the members when the latter are moved adjacent to and in contact with each other.

4. A closure device for cloths and other articles made of flexible materials comprising flanged edges to be united and separated, a flexible band, fastening members fixed in spaced relation to said band and slideable on said flanged edges, a leading member also fixed to said band and having holes accommodating the said flanged edges and locking means associated with said leading member and passing through said holes to exert a jamming action on the said flanged edges to lock said leading member in any position on the flanged edges.

5. A closure device for cloths and other articles made of flexible materials comprising flanged edges to be united and separated, a flexible band, fastening members fixed in spaced relation to said band and slideable on said flanged edges, a leading member also fixed to said band and having holes accommodating the said flanged edges, members in the form of cords passing through the holes in the leading member in contact with the flanged edges, parts of said members being of different thickness, and means whereby the parts of different thicknesses of the members are caused to occupy the holes in order to operate the closure device and to lock the leading member in any position on the flanged edges.

6. A closure device for cloths and other articles made of flexible materials comprising flanged edges to be united and separated, a flexible band, fastening members fixed in spaced relation to said band, lateral openings in said fastening members receiving said flanged edges, plates provided at the ends of the flanged edges, sliders mounted on said plates to be moved to and from said flanged edges, said sliders forming stops for the fastening members when located adjacent the flanged edges, and said plates passing through said openings when the sliders are moved away from the flanged edges whereby the fastening members may be mounted on or separated from the flanged edges.

7. A closure device for cloths and other articles made of flexible materials, comprising flanged edges to be united and separated, a flexible band, fastening members fixed in spaced relation to said band and slideable on said flanged edges, a leading member also fixed to said band and having holes accommodating the said flanged edges, and flexible members passing through the said holes to move the leading member along the flanged edges.

8. A closure device for cloths and other articles made of flexible materials comprising flanged edges to be united and separated, fastening members, side openings in the said fastening members accommodating said flanged edges, a flexible band, the fastening members fixed in spaced relation to said band, notches in the side faces of the fastening members to accommodate the folds of the band when the fastening members are moved towards each other and the band surrounding the lower part of the fastening members and being fixed thereto substantially in the central plane passing through the side openings.

APOLLON TCHEKHOVITCH.
